(57) **CLAIM**

The ornamental design for a rail pocket, as shown and described.

DESCRIPTION

FIG. 1 is an isometric view of a rail pocket showing my new design;

FIG. 2 is a left side view thereof;

FIG. 3 is a top view thereof;

FIG. 4 is a bottom view thereof;

FIG. 5 is a rear view thereof; and,

FIG. 6 is a front view thereof.

The shading lines shown in the drawings represent the approximate three-dimensional contour of the design, and are not intended to indicate surface decoration.
